CLAIM

The ornamental design for a flip-flop style footwear, as shown and described.

DESCRIPTION

FIG. 1 is a perspective view of a flip-flop style footwear showing my new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

Shown is a flip-flop style footwear for the left foot. The flip-flop style footwear for the right foot has a symmetrical figure.
